FLUSHING CISTERN

Filed Jan. 20, 1925

Inventor
W. C. D. NORTH
By James Guerne Atty

UNITED STATES PATENT OFFICE.

WILLIAM CHARLES DINGEY NORTH, OF DUNEDIN OTAGO, NEW ZEALAND.

FLUSHING CISTERNS.

Application filed January 20, 1925. Serial No. 3,662.

To all whom it may concern:

Be it known that I, WILLIAM CHARLES DINGEY NORTH, a subject of King George V of Great Britain, residing at 40 Dowling Street, Dunedin Otago, in the Dominion of New Zealand, have invented certain new and useful Improvements in Flushing Cisterns, of which the following is a specification.

This invention relates to flushing cisterns commonly used in lavatories.

The object of the invention is to provide an approximately silent flusher of inexpensive construction.

The following is a description of the apparatus, with reference to the accompanying drawings,

Figure 1 is a sectional elevation of the cistern through line A—B, of Fig. 3, showing relative positions of the various parts when the cistern is empty.

In this figure it will be seen that the float and trip members are quite free to use, when the incoming water causes their displacement.

Figure 2 is also a sectional elevation of cistern through line A—B, of Fig. 3, showing relative positions of the various parts when the cistern is full.

In this view the relative position of the outlet valve and the members necessary for its movement, when actuated upon to flush, is indicated by dotted lines.

Figure 3 is a plan view of Figure 2, the cover being removed.

Figure 4 is an end view of the cistern showing inlet and interchangeable overflow.

Figure 5 is an enlarged sectional view of the valve, showing the spring supported weight.

Figure 6 shows in detail the end portion of the valve actuating lever.

Figure 7 is a plan view of the trigger.

Figure 8 is a side view illustrating in enlarged detail the trip mechanism.

There is an ordinary inlet valve 1 with which a ball cock lever 2 is pivotally suspended at 3, the float of the said ball cock lever being indicated at 4. There is a valve consisting of a weighted portion 5 mounted on a spindle 6, and having a circular recess 7 cast in its under surface to allow the end portion of a helical spring 8 being housed therein. There is a disc 9 which is either cast integral with the spindle 6, or fitted thereto as a separate member; the under surface of the disc 9 is faced with a suitable

jointing material 10, which is secured to the said disc, and by means of a nut 11 screwed upon the spindle 6. The said spindle provides a guide for the valve by engaging 60 with a guide member 12 fixed to the interior of the outlet fitting 13.

There is a valve seat 14 formed on the outlet fitting 13, which is secured to the bottom 15 of the cistern, having suitable jointing material, as at 16 to prevent leakage; the nut 17 which is adapted to screw upon a thread formed on the said outlet secures it to the cistern, as it frequently happens in fittings of this class the jointing material is 70 damaged by the fitting 13 turning with the nut 17, when adjusting the fitting to fix it to the bottom or detach it, provision is made to prevent the said outlet member from turning, by casting a lug 13^A on the flange 13^B 75 of the outlet 13, and by casting pins 15^A on the inner surface of the bottom 15 of the cistern. The lug 13^A is adapted to fit between the pins 15^A, as indicated in Figure 3.

There is a push rod 18 having a knob 19 80 projecting through the cover of the cistern, the said push rod 18 is pivotally connected with the valve lifting lever 20, and the said lever 20 being pivotally mounted upon a bracket 21 at 22.

The lever 20 is pivotally linked with the valve, as indicated at 23; the said lever 20 is bent at 20^A and 20^B as shown in Figure 6, so that the portion 20^C is approximately at right angles to the valve lifting lever 20, 90 the edge 20^D in the portion 20^C being preferably of triangular section, the face 24 being the under surface to provide a better contact surface with the combined holding and releasing member; (hereinafter referred to as 95 the trigger member 25) the said trigger is pivoted to a bracket 26, which is adjustably attached to the ball cock lever 2 by means of a stud 27 and the jamb nut 27^A.

Now describing the operation of the valve 100 by the specially designed trip gear, the water in the cistern is maintained at the level indicated at 28 in Figure 2, on the valve 1 being in its closed position as in Figure 2, and the ball cock lever 2 and float 4 being 105 in the position indicated in full lines in the same figure. To release the water for flushing purposes, pressure is put upon the knob 19 of the push rod 18 to depress it sufficiently to enable the portion 20^C of the valve 110 lifting lever 20 to tilt the trigger 25; the said portion 20^C passes the said trigger to

clear and permit it to return to normal position, and upon releasing the pressure on push rod 18 the lever 20 recedes until the portion 20^c comes to rest in contact with the surface 25^a of the trigger 25, whereby the valve is held in open position, as indicated by broken lines in Figure 2, until the water level in the cistern is reduced to the approximate minimum on being discharged for flushing operation.

As the water discharges through the outlet 13, the ball cock lever follows the decreasing water level, until it assumes its lowest position indicated in Figure 1, and in that position or approximately so, the point 25^b of the trigger 25 becomes disengaged with the part 20^c of the valve lifting lever 20. The point 25^b of the said trigger 25 describes an arc indicated by broken lines at 29 in Figures 1 and 2, and upon reaching the point 29^a, the outlet valve engages with its seat 14, closing the outlet orifice and the water discharging through the inlet valve 1, refills the cistern ready for the next operation.

What I claim as new and desire to secure by Letters Patent is:—

1. In a flushing tank having an inlet valve, an outlet valve, a ball cock lever for controlling the inlet valve in accordance with the level of fluid in the tank, a manually operable lever connected to and adapted to operate the outlet valve, and means carried by the ball cock lever to support the manually operable lever and thereby the outlet valve in open position during movement of the ball cock lever incident to the lowering of the level of the liquid in the tank, said ball cock lever carried means automatically releasing the manually operable lever at a predetermined liquid level in the tank.

2. In a flushing tank, an inlet valve, an outlet valve, a ball cock lever for controlling the inlet valve, a manually operable lever for actuating the outlet valve, a trigger carried by the ball cock lever, and an extension

on the manually operable lever to be engaged and supported by the trigger to hold the manually operable lever and thereby the outlet valve in open position during movement of the ball cock lever incident to the receding level of the liquid in the tank, said trigger and manually operable lever moving on opposing curved lines in operation to cause the lever to be released from the holding action of the trigger at a predetermined level of liquid in the tank.

3. In a flushing tank, an inlet valve, a ball cock lever controlling the same, a trigger carried by said lever and capable of independent upward movement but prevented from downward movement, an outlet valve, a manually operable lever connected to said valve, and an extension on said lever to engage and upwardly displace the trigger to permit the trigger to ride beneath and support said manually operable lever during the greater portion of the downward movement of the ball cock lever in the receding level of the liquid in the tank.

4. In a flushing tank, an inlet valve, a ball cock lever controlling the same, a trigger carried by said lever and capable of independent upward movement but prevented from downward movement, an outlet valve, a manually operable lever connected to said valve, and an extension on said lever to engage and upwardly displace the trigger to permit the trigger to ride beneath and support said manually operable lever during the greater portion of the downward movement of the ball cock lever in the receding level of the liquid in the tank, the movement of the ball cock lever in the descent of the liquid level serving to gradually withdraw the trigger as a support for the manually operable lever and to finally relieve the manually operable lever from the support of the trigger at a predetermined level of liquid in the tank.

In testimony whereof I have hereunto set my hand.

WILLIAM CHARLES DINGEY NORTH.
